UNITED STATES PATENT OFFICE.

RUSSELL W. BAKER, OF ANDERSON, INDIANA, ASSIGNOR, BY MESNE ASSIGNMENTS,
TO DELCO-REMY CORPORATION, OF DAYTON, OHIO, A CORPORATION OF DELAWARE.

ARMATURE-INSULATION-CUTTING MACHINE.

Application filed March 15, 1926, Serial No. 94,991. Renewed September 15, 1927.

This invention relates to the manufacture of dynamo electric machines, and particularly to that part of the process of manufacture which includes insulating the armature core. It has been the practice to wrap about the sides and peripheries of the core teeth a single strip of sheet insulating material, and then to cut this material at the edges of the core teeth after the windings are placed on the armature core so as to remove those superfluous portions of the insulating material which overlie the core teeth peripheries and to leave only those portions which line the core slots.

15 One of the objects of the invention is to reduce the cost of removing the superfluous insulating material referred to. In order to accomplish this object the present invention provides apparatus including means for
20 guiding an armature core while it is moved endwise relative to devices which simultaneously cut the insulation at the edges of the core teeth in order to remove these superfluous portions which overlie the core teeth
25 peripheries.

Further objects and advantages of the present invention will be apparent from the following description, reference being had to the accompanying drawings, wherein a preferred form of embodiment of the present invention is clearly shown.

In the drawings:

35 Figs. 1 and 2 are fragmentary views of an armature core showing that part of the process of manufacture to which the present invention relates.

Fig. 3 shows diagrammatically portions of the apparatus included in the present invention.

40 Fig. 4 is a sectional view on the line 4—4 of Fig. 3.

Fig. 5 is a plan view, partly in transverse section, of the apparatus embodying the pres-

45 Fig. 6 is a longitudinal sectional view

Figs. 5 and 6 are drawn to a smaller scale

Referring to Figs. 1 and 2, 20 designates an armature core which is mounted on an armature shaft 21. Before applying windings to the core, there is wrapped about the core teeth a single strip 22 of sheet insulating material. The end portions of this strip overlap

each other in one of the core slots and these overlapping portions are designated by numerals 22^a and 22^b in Fig. 1. The next step is to wind into the armature slots windings which are represented in Figs. 1 and 2 by the small circles 23. After this is done the armature core insulation is cut at the edges 24 of the core teeth in order that the portions 25 which overlie the armature core teeth peripheries may be removed. It is apparent that these portions 25 serve to hold the slot lining portions in position while the windings are being applied and to cover the edges of the core teeth to prevent stripping the insulation from the wire. After winding the armature, these portions are superfluous and must be removed in order that the armature may be ground to true concentricity with its shaft.

The apparatus for cutting the insulation strip 22 at the core edges 24 includes a plurality of cutting rollers 26, each of which is adapted to be received by one of the core slots and to cooperate with adjacent core teeth in order to shear the insulation strip 22 at the core teeth edges 24. The mechanism for operating upon an armature core in the manner described includes a block 30 having a central aperture 31 for guiding the armature core 20 while it is moved endwise against a plurality of the cutting wheels 26 which are supported radially by the block 30. Each wheel 26 is mounted on an axle 32 carried by a bifurcated wheel supporting block 33. The blocks 33 are guided by radially extending slots 34 provided by the block 30. Each wheel 26 is maintained in position for cutting the armature core insulation strip 22 by a screw 35 which bears against the block 33 and is threadedly connected with a bar 36 attached by screws 37 to the block 30. By turning the screw 35 the wheel 26 may be moved nearer to the core 20, and the screw 35 is secured in adjusted position by a lock nut 38.

The block 30 is attached by screws 40 to a base 41 which is slidably supported upon a plate 42 to which guides 43 are attached by screws 44. The base 41 is slidable by the stops 45 and 46 attached to the plate 42. When the block 30 is in the position shown in Figs. 5 and 6, an armature core may be applied to it. Then the block 30 is moved by a handle member 47 toward the left until the base 41 engages the stop 46. In this position of the base 41 the armature core 20 will be brought

into alignment with a plunger 48 which is operated by the head of a punch press not shown. It will be understood that the horizontal bed of the punch press supports the plate 42. In 5 this position of the base 41, the central aperture 31 in the block 30 will be located vertically above an aperture 49 in the plate 42. The punch press is then operated to cause the plunger 48 to descend in order to force the 10 core 20 downwardly through the openings 31 and 49. During this downward movement of the core 20, the wheels 26 will engage the armature insulation strip 22 as indicated in Fig. 2 in order to cut the strip at the edges 15 of the armature core teeth.

The plunger 48 is provided with a spherical recess 50 for receiving the overlapping portions 23^a of the armature windings, and with a cylindrical recess 51 for receiving one 20 end of the armature shaft 21. The plunger 48 is provided with grooves 52 which receive the cutting rollers 26 during a portion of the downward movement of the plunger 48. These grooves 52 divide the lower edge 25 portion of the plunger 48 into segments 53. These segments 53 are the only portions of the plunger 48 which engage the armature core 20 in order to move it downwardly as viewed in Figs. 3 and 6. The windings are 30 not injured by the apparatus since pressure is not applied to them; and the shaft 21 is not shifted relative to the core 20 by the operation of the apparatus since the plunger 48 does not apply pressure to the shaft 21.

35 The punch press will return the plunger 48 to the upper position shown in Fig. 6 so that it will clear the upper end of the shaft 21. Then the handle 47 may be grasped by the operator in order to move the block 30 toward the right so that the work may be inserted into the apparatus. The armature and the superfluous portions of insulation 25 which have been removed are received by a suitable hopper located below the opening 45 49 in the plate 42.

It will be noted also that the rollers 26 will compact the windings 23 and will cause portions 22^c of the slot lining insulation to be pressed against the windings as shown in 50 Fig. 2.

55 It is apparent that the present invention provides for rapidly removing the superfluous portions of insulating material from the armature core. This work can be done as rapidly as the operator can insert the work in the fixture and operate the punch press. As considerable time has been saved, the cost of this portion of the manufacture of an armature is materially reduced.

60 While the form of embodiment of the present invention as herein disclosed, constitutes a preferred form, it is to be understood that other forms might be adopted, all coming

within the scope of the claims which follow.

What is claimed is as follows:

65

1. An armature core insulation cutting machine comprising, in combination, means for guiding the core, means for moving the core endwise through the guide, and means entering the core slots and co-operating with the 70 core teeth to cut the insulation at edges of the core teeth.

2. The machine as defined by claim 1, in which the guiding means is adapted to be supported by the bed of a punch press, and the moving means is a plunger adapted to be attached to the head of a punch press and is provided with recesses for receiving the armature shaft and windings and with surfaces which bear only against one end of the 80 armature core.

3. The machine as defined by claim 1, in which the cutting means comprises a plurality of cutting wheels supported by the guide in radial alignment respectively with the 85 slots in the core.

4. An armature core insulation cutting machine comprising, in combination, means for guiding the core, means for moving the core endwise through the guide and means entering the core slots and cooperating with the 90 core teeth simultaneously to cut the insulation at adjacent edges of side by side core teeth.

5. An armature core insulation cutting 95 machine comprising, in combination, means for holding a slotted core member having sheet insulation adjacent its teeth and lining its slots, a member adapted to enter a core slot and to cooperate simultaneously with 100 adjacent peripheral edges of adjacent core teeth to sever the insulation, and means for producing movement of the core member relative to the severing member.

6. An armature core insulation cutting machine comprising, in combination, means for holding a slotted core member having sheet insulation engaging its teeth and lining its slots, a plurality of cutting wheels each 110 adapted to enter a core slot and to cooperate simultaneously with adjacent peripheral edges of adjacent core teeth to sever the insulation, a member for supporting said cutting wheels in radial alignment respectively 115 with the slots of the core member, and means for producing movement of one of said members relative to the other.

7. The machine as defined in claim 6 in which each cutting wheel is so shaped as to engage the severed edges of the core slot lining insulation and to push the same into the core slot.

In testimony whereof I hereto affix my signature.

RUSSELL W. BAKER.
